(57) CLAIM

The ornamental design for a combination stackable tray and bowls, as shown and described.

DESCRIPTION

FIG. 1 is a perspective view of a combination stackable tray and bowls, showing my new design;

FIG. 2 is a side view thereof; and,

FIG. 3 is another perspective view thereof.

The broken lines shown in FIG. 3 are included for the purpose of illustrating structural environment and form no part of the claimed design.
